UNITED STATES PATENT OFFICE.

GOTTLOB BINDER, OF ROCHESTER, NEW YORK, ASSIGNOR TO AMERICAN LAUNDRY MACHINERY COMPANY, OF CINCINNATI, OHIO, A CORPORATION OF OHIO.

SAFETY DEVICE FOR CENTRIFUGAL EXTRACTORS.

1,162,847.

Specification of Letters Patent.

Patented Dec. 7, 1915.

Application filed July 19, 1913. Serial No. 779,953.

To all whom it may concern:

Be it known that I, GOTTLB BINDER, of Rochester, in the county of Monroe, State of New York, have invented certain new and useful Improvements in Safety Devices for Centrifugal Extractors; and I do hereby declare the following to be a full, clear, and exact description of the same, reference being had to the accompanying drawings, forming a part of this specification, and to the reference-numerals marked thereon.

My present invention relates to centrifugal extractors, with more particular reference to such machines as are employed for drying different materials as for instance clothes in laundries, and it has for its object the provision of a novel and improved arrangement of safety devices that will overcome some of the defects present in the machines now generally in use.

A further object of my invention consists in providing a locking device for the cover of the extractor which will prevent the cover from being opened when the machine is in operation and also prevent starting the machine when the cover is open.

Still another object of my invention resides in the provision of novel speed controlled mechanism which is so arranged as to prevent the extractor cover from being opened until the machine has come to a standstill.

To these and other ends the invention consists in certain improvements and combinations of parts, all as will be hereinafter more fully described, the novel features being pointed out in the claims at the end of the specification.

In the drawings: Figure 1 is a view in side elevation of a centrifugal extractor equipped with a preferred embodiment of my invention; Fig. 2 is an enlarged elevation, partly in section, of the locking means for the cover; Fig. 3 is a plan view of the same; Fig. 4 is a plan view of the entire apparatus; Fig. 5 is a view similar to Fig. 2, showing the cover in raised position; Fig. 6 is a side elevation of the parts shown in Fig. 5, looking toward the right of the figure; Fig. 7 is a sectional view on the line $\alpha-\alpha$ of Fig. 1; Fig. 8 is a vertical sectional view; Fig. 9 is a detail bottom plan view, and Fig.

10 is a transverse sectional view showing the upper portion of Fig. 8 in plan.

Similar reference numerals throughout the several figures indicate the same parts.

In the present embodiment of my invention, 1 designates the base of the extractor which may be of usual form, and 2 is the body portion, while 3 designates the rotat- 60 ing receptacle within which the clothes or other materials are placed when the water is to be extracted.

4 is an extractor cover, carrying bracket arms 5 which are journaled on the rod 6, the latter serving as a support for the cover. One of the bracket arms 5 is provided with an extension 7 which carries a curved abutment or bar 8 for a purpose that will appear presently.

In machines of this character, it is highly desirable to automatically control the cover in such a way that it cannot be opened until the machine has come to a complete standstill, and further, so that the machine can- 75 not be started while the cover is open. It is essential that a single locking device be provided for the cover, which is so connected to a plurality of controlling members, that the several purposes referred to may be ac- 80 complished with a construction that is at once simple and easy to manufacture. To these ends, I provide a locking device, pref- erably in the form of a rod 9 which is ver- 85 tically movable in the guide 10, being pro- vided with stops 11 to limit its movement upwardly and downwardly. The rod 9 is provided with an opening or recess 12 adapted to receive the abutment 8 on the cover when the locking device is raised, as 90 shown in Fig. 5.

The operation of raising and lowering the locking rod 9 may be accomplished in different ways, and is preferably manually controlled. For this purpose, there is provided 95 a hand lever 13, which is pivotally mounted at 14, and carries a segmental rack 15, ar- ranged for engagement with the rack 16, the latter being secured upon the locking rod 9, as shown in Fig. 5. It will be seen 100 that when the locking rod is raised to the position of Fig. 5, the cover may be opened, and when the locking rod is lowered it is impossible to open the cover. These move-

ments of the locking device are accomplished preferably by hand, through the means I have just described, and it is connected up in a manner as will presently be made clear, so as to prevent it from being moved by the manually controlled means, except when the machine is not in motion.

The receptacle 3 is mounted on the vertical shaft 17 that carries a pulley 18, driven by the belt 19 which engages pulley 20 mounted on the shaft 21. The shaft 21 carries the fixed pulley 22, and the loose pulley 23, motion being transmitted thereto from a suitable source of power by a belt, the position of which is controlled by the belt shifter 24. The shifter 24 carries a bracket 25 having an opening 26 therein for a purpose that will appear hereinafter, and is further provided with a handle 27 by which the shifter 24 may be moved back and forth to effect starting and stopping of the machine. When the shifter 24 has moved the belt onto the fast pulley, it is desirable to lock the cover against opening, and when the cover is open, it is desirable to prevent movement of the shifter so as to start the machine. To this end, the locking device described hereinbefore is pivotally connected to a bar 28 which is fixed upon the rock shaft 29. The bar 28 carries at its outer end a pivotally mounted vertically extending rod 30 which moves in the guide 31 and is adapted to engage the aforementioned opening 26 of the shifter. Thus it will be seen that when the shifter 24 is in the position shown in Figs. 1 and 4, the opening 26 will be in line with the rod 30 which passes therethrough when raised. This permits the locking device 9 to be operated to enable the cover to be opened. When, however, the machine is in operation and the belt shifter is moved to bring the belt into engagement with the fixed pulley 22, the opening 26 will be out of alignment with the rod 30, and the latter cannot, therefore, be raised. As long as this condition exists, the locking device 9 is held against movement, the cover being locked in its closed position. It will be evident that the machine will run for a greater or less period of time after the power belt is shifted to the loose pulley, and that with only the locking device thus far described, the cover might be opened while the receptacle is still in motion. This is extremely dangerous and has not infrequently been the cause of serious accidents, when an operator reaches into the receptacle before it has stopped rotating, and catches an arm or hand in the heavy wet materials which are still moving with considerable momentum until the machine comes to a complete standstill. It is to obviate this possibility that I have provided a speed controlled mechanism which is also connected with the locking device 9, and in such a manner as to prevent any

movement of it until the extractor receptacle has entirely stopped moving. For accomplishing this, I provide arms 32 which are fixed upon the rock shaft 29 and are pivotally connected at 33 to the shoes 34 which are mounted on blocks 35. The latter are arranged beneath and engage with the lower face of a ring 36 which has an integral collar 37 in engagement with the bushing 38, the latter being fixedly mounted on the shaft 17. The ring 36 is also provided with inclined ways or recesses 39 to receive the balls 40 which normally occupy the position shown in Fig. 8, resting against the collar 37. Also fixedly mounted on the bushing 38 is a collar 41 provided with the arms 42, which have downwardly projecting extensions 43 and flanges 44, co-operating with the balls 40 whereby to limit the outward movement of the latter and also to prevent upward movement of the ring 36 when the balls 40 are in the position shown in Fig. 8. When the machine is at rest, the balls 40 are in their innermost positions so that when the locking device 9 is raised, the arms 32 can likewise be elevated, while the ring 36 moves upwardly on the bushing 38. When the machine is in motion, however, the balls 40 are thrown outwardly by centrifugal force far enough so that they lie beneath the flanges 44 and are engaged thereby upon vertical movement of the ring 36. This serves to effectually prevent the locking device 9 from being raised at all until the shaft 17 has entirely stopped its movement, or at least so nearly that no harm could be done by raising the cover. It has been found by actual experiment that, as a matter of fact, the cover cannot be lifted until the machine is practically stopped. That is to say, as long as the balls 40 are ever so slightly removed from engagement with the collar 37 by centrifugal action, they will engage the flanges 44 and retain the locking device in its lowered position.

I claim as my invention:

1. In a centrifugal extractor, the combination with a starting member, of a cover, a locking device co-operating with the cover, a manually operated device associated with the locking device and acting to move it into and out of locking position, and means associated with the locking device and arranged to engage the starting member so as to prevent movement of the latter when the locking device is in unlocking position and to prevent movement of the locking device when the starting member is shifted to starting position.

2. In a centrifugal extractor, the combination with a cover, of a locking device co-operating with the cover, a manually operated device associated with the locking device and acting to move it into and out of locking position, and speed controlled means

in operative relation with the locking device so as to prevent movement thereof when the machine is in operation.

3. In a centrifugal extractor, the combination

5 with a starting member, of a cover, a locking device coöperating with the cover, a manually operated device associated with the locking device and acting to move it into and out of locking position, means associated

10 with the locking device and arranged to engage the starting member so as to prevent movement of the latter when the locking device is in unlocking position and to prevent movement of the locking device when 15 the starting member is shifted to starting position, and speed controlled means in operative relation with the locking device so as to prevent movement thereof when the machine is in operation.

20 4. In a centrifugal extractor, the combination with a cover, of a locking device co-operating with the cover, a manually operated device associated with the locking device and acting to move it into and out of locking position, and automatically actuated means for preventing movement of the locking device.

5. In a centrifugal extractor, the combination with a cover, of a starting member, a locking device coöperating with the cover, a manually operated device associated with the locking device and acting to move it into and out of locking position, and means governed by the starting member for preventing movement of the locking device.

30 6. In a centrifugal extractor, the combination with a cover, of a starting member, and a cover locking device coöperating with the starting member, the latter being locked 40 when the cover is unlocked, and a manually operated device associated with the locking device and acting to move it into and out of locking position.

45 7. In a centrifugal extractor, the combination with a cover, of a locking device co-operating with the cover, a manually operated device associated with the locking device and acting to move it into and out of locking position, and speed controlled means 50 in operative relation with the locking device to prevent movement thereof.

55 8. In a centrifugal extractor, the combination with a cover, of a starting member, a locking device coöperating with the cover, a manually operated device associated with the locking device and acting to move it into and out of locking position, means governed by the starting member for preventing movement of the locking device, and speed

controlled means in operative relation with 60 the locking device to prevent movement thereof.

9. In a centrifugal extractor, the combination with a cover, of a locking device co-operating with the cover, a manually operated device associated with the locking device and acting to move it into and out of locking position, a belt shifter, and a connection from the locking device adapted to interlock with the shifter. 65

10. In a centrifugal extractor, the combination with a cover, of a locking device co-operating with the cover, a manually operated device associated with the locking device and acting to move it into and out of locking position, a belt shifter, a connection from the locking device adapted to interlock with the shifter, and speed controlled means 70 also connected to the locking device.

11. In a centrifugal extractor, the combination with a cover, of a locking device co-operating with the cover, a manually operated device associated with the locking device and acting to move it into and out of locking position, a shifter having an opening, a rod connected to the locking device and coöperating with the opening in the shifter, and speed controlled means also connected with the locking device. 80

12. In a centrifugal extractor, the combination with a cover, of an abutment carried by the cover, a locking device having an opening to receive said abutment, a lever in operative engagement with the locking device for moving the same, a shifter having 95 an opening, a rod connected to the locking device and coöperating with the opening in the shifter, and speed controlled means also connected to the locking device. 90

13. In a centrifugal extractor, the combination with a cover, of an abutment carried by the cover, a locking device having an opening to receive said abutment, a lever operatively connected to the locking device for moving the same, a shifter having an 105 opening, a rod connected to the locking device and coöperating with the opening in the shifter to lock the shifter against movement when the locking device is elevated, and speed controlled means connected to the 110 locking device and operating to lock the same against movement when the extractor is in operation. 100

GOTTLOB BINDER.
